Primary Examiner — Patricia A Palasik(74) *Attorney, Agent, or Firm* — Norton Rose Fulbright US LLP(57) **CLAIM**

The ornamental design for an automatic guided transport vehicle, as shown and described.

DESCRIPTION

FIG. 1 is a front elevation view of an automatic guided transport vehicle of our new design;

FIG. 2 is a back elevation view of the automatic guided transport vehicle shown in FIG. 1;

FIG. 3 is a left side elevation view of the automatic guided transport vehicle shown in FIG. 1;

FIG. 4 is a right side elevation view of the automatic guided transport vehicle shown in FIG. 1;

FIG. 5 is a top plan view of the automatic guided transport vehicle shown in FIG. 1;

FIG. 6 is a perspective view of the automatic guided transport vehicle shown in FIG. 1;

FIG. 7 is another perspective view of the automatic guided transport vehicle shown in FIG. 1; and,

FIG. 8 is another perspective view of the automatic guided transport vehicle shown in FIG. 1.

The bottom view is omitted because it has no essential features.

1 Claim, 4 Drawing Sheets(56)
